The ornamental design for a card connector, as shown and described.

DESCRIPTION

FIG. 1 is a top, front and left side isometric view of a card connector showing my new design, with phantom lines indicating a cable with which the connector is used;

FIG. 2 is a front elevation view thereof;

FIG. 3 is a plan view thereof;

FIG. 4 is a rear elevation view thereof;

FIG. 5 is a bottom view thereof; and,

FIG. 6 is a right side elevation view thereof, the left side being identical thereto.

The broken line showing of the cable in FIGS. 1, 3, 5 and 6 is included for the purpose of illustrating environmental structure only and forms no part of the claimed design.
